(57) **CLAIM**

We claim the ornamental design for a case of electrical receptacle, as shown and described.

DESCRIPTION

FIG. 1 is a perspective view of a case of electrical receptacle showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

In the drawings, the broken lines depict environmental subject matter only and form no part of the claimed design.
